UNITED STATES PATENT OFFICE.

IRVING POTTRUCK AND NORMAN SHALIT, OF NEW YORK, N. Y.

PHOTOGRAPHIC-PRINT-WASHING MACHINE.

Application filed July 27, 1920. Serial No. 399,383.

To all whom it may concern:

Be it known that we, IRVING POTTRUCK and NORMAN SHALIT, the former a citizen of the United States and the latter a citizen of 5 Russia, residing at New York city, in the county of New York and State of New York, have invented certain new and useful Improvements in Photographic-Print-Washing Machines, of which the following is a specification.

This invention has relation to photographic print washing machines, and has for an object to provide a machine for the purpose of washing photographic prints or the like and consists of a plurality of rotatable elements in which the prints are enclosed and which are designed to rotate in a bath, with a specific power mechanism operating upon the friction transmission principle for 15 the purpose of communicating rotary motion to said rotatable elements with means for disconnecting communication when desired.

A still further object of the invention is to 20 provide a photographic print washing machine of the character above set forth comprising a plurality of rotatable drums in which the prints are enclosed and rotated in a bath, said drums being mounted in such a 25 manner that they may be independently elevated to a position above the bath when desired for the purpose of removing the washed prints or for charging the drum.

In addition to the foregoing this invention 30 comprehends improvements in the details of construction and arrangement of parts to be hereinafter described and particularly set forth in the appended claims.

In the accompanying drawings in which 35 similar and corresponding parts are designated by the same characters of reference throughout the several views in which they appear.

Figure 1 is a view of the machine in front 40 elevation with the tank and supporting members shown in section.

Figure 2 is a view thereof in top plan.

Figure 3 is a view of the machine in transverse section, and

Figure 4 is a detail view.

Figure 5 is a detail perspective view.

With reference to the drawings, 10 indicates a trough like receptacle in which the bath is contained, said trough being substantially semi-circular and supported upon

three members, more or less, each supporting member consisting of a vertical portion 11, a horizontal bent portion 12 extending beneath the trough and another vertical portion supporting the forward side of the 60 trough. The upper ends of the members 11 are connected by a horizontal bar as shown. An overflow pipe 14 is provided which is located horizontally and longitudinally of the trough adjacent the upper and rear edge 65 thereof as shown. This pipe is perforated at places to draw away the excess water when the same has reached a desired level. The pipe 14 also serves as a support for rectangular frames 15 of which three are provided. Each frame consists of the longitudinal members 16 and the transverse members 17, each member 17 having its rear end formed with a semi-circular portion 18 which rests upon the pipe 14, while the opposite 70 ends of the members 17 are designed to rest upon the edge of the trough. The intermediate portions of the members 17 are offset as at 19 to form a support for ball bearing 75 cages 20. Within each frame 15 there is 80 located a drum 21 of foraminous material, each drum having a pair of end trunnions 22 which rests in the ball bearing cages 20 and thus support the drums for rotation. One or both ends of each drum as desired is 85 formed of a metallic band 23 of a purpose to be presently noted. A supporting device is also provided which consists of a twisted partly curved bar 24 having its forward end pivoted to the intermediate portion of the 90 forward member 16 of each frame, 15. Obviously, three of said bars 24 will be provided as in the present instance and the rear end of each bar 24 operates in a slot formed in the connecting bar 13. The slot 95 it will be noted is cut from the top edge of said bar; and to close the upper end of said slot we provide connecting members 25 which are bolted to the members 13 as shown. When the frame 15 is in a lowered position 100 it is supported upon the forward edge of the trough as explained above. However, when the frame has been elevated it may be supported in an elevated position by reason of the fact that the edge of the member 18 may 105 rest in a slot 25 formed in the underside of each bar 24, as shown in dotted lines in Figure 3. We also provide an inlet which consists of a pipe 27 located in the bottom of the trough, extending longitudinally thereof and 110

entering at one end, said pipe having a row of perforations at each side which are oppositely disposed and directed downwardly slightly so as to direct the water toward the bottom of the trough and cause it to circulate upwardly by contact with the curved sides of the trough.

We also provide a power means for operating the drum which consists of a shaft 28 mounted in bearings 29 which in turn are located upon the upper ends of the members 11. The shaft carries three relatively small pulleys 30 around which belts 31 are trained, the belts also passing around relatively large pulleys 32 which are mounted upon stub-shafts 33. Each stub-shaft is supported in a swinging arm 34, the opposite end of each arm being supported upon the shaft 28 so as to swing in a vertical arc. To the opposite end of each shaft 33 there is mounted a friction wheel 35 which is preferably constructed of wood and designed to bear upon the end band 23 of the drum. One end of the shaft 28, is provided with a pulley around which a belt passes, said pulley being indicated at 36. The pulley is intended to be driven by motor, hand power or any other method desired or found convenient.

It will be readily seen that when the drums are in a lowered position and partly submerged within the bath with the friction members 35 resting thereupon, any power transmitted to the shaft 28 will be communicated through the belt 31 to the wheels 32 and friction pulleys 35 thus rotating the drum. The prints are previously inserted in the drums through a door opening which is normally closed by means of a hinged door 37. Said door may be held in closed position through any convenient form of catch or lock. The water issuing through the perforations of the tube 27 will be directed downwardly and upwardly and circulate around the drum during rotation thereby of thoroughly washing the prints contained therein. When it is desired any one of the drums may be elevated by hand and retained in elevated position through the medium of the bar 24 in the manner described. Also, power may be disconnected from any one of the drums if desired by merely lifting the arm 34 corresponding to said drum. To hold the arm 34 in elevated position we provide a curved support 38 which is pivoted to the under side of the member 34 and extends through an opening in the bar 13. The underside of each member 38 is provided with a slot 38' so that when the bar 34 is raised said slot may receive the edge of the member 13 to thus retain the member 34 in elevated position. Thus, any one of the drums may be selected to operate or to be disconnected at will, and if desired all three of said drums may be elevated and the power disconnected from all

three if desired while permitting the shaft 28 to continue to rotate. Other uses and arrangements will readily occur to those familiar to the art to which this invention appertains. We also provide a drain pipe 39 for cleaning the trough.

While we have illustrated and described our invention with some degree of particularity, we realize that in practice various alterations therein may be made. We therefore reserve the right and privilege of changing the form of the details or otherwise altering the arrangement of the correlated parts without departing from the spirit of the invention or the scope of the appended claims.

Having thus described our invention what we claim as new and desire to secure by United States Letters Patent is:—

1. A photographic print washing machine including a bath containing element, a print containing element partly submerged therein, a constantly operating driving element, and means for transmitting motion between the operating element and the print containing element including an endless member contacting with a portion of the print containing element.

2. A photographic print washing machine including a bath containing element, a print containing element partly submerged therein, a constantly operating driving element, and means for transmitting motion between the operating element and the print containing element including an endless member contacting with a portion of the print containing element, and moving the print containing element by frictional contact therewith.

3. A photographic print washing machine including a bath containing element having an open top, a print containing element partly submerged therein, a constantly operating driving element, and means for imparting movement to the print containing element from the constantly operating element including an endless member frictionally contacting with the print containing element and positioned above the open top of the bath containing element.

4. A photographic print washing machine including, a bath containing element, a plurality of drums partly submerged therein, and mounted for rotation, a constantly rotating shaft, and a plurality of friction drive elements driven from said shaft each one being adapted for independent connection with one of the drums to operate the same.

5. A photographic print washing machine including a bath containing element, a plurality of rotary drums partly submerged therein, and independent supporting means for each drum permitting the same to be elevated, a single drive shaft, and a plurality

- of friction drive elements driven therefrom each for an independent connection with one of the drums.
6. A photographic print washing machine including a bath containing element, a plurality of frames mounted therein, for vertical movement, a drum mounted in each frame for rotation, means for elevating any of the drums above the bath containing element, and a separate drive means for each drum.
7. A photographic print washing machine including a bath containing element, a plurality of drums mounted therein for rotation, a drive shaft, a plurality of arms loosely mounted on the drive shaft, a friction wheel carried by each arm for engagement with one of the drums, and means for communicating motion between the shaft 20 and said friction wheels.
8. A photographic print washing machine including a bath containing element, a plurality of drums mounted therein for rotation, a shaft, a plurality of arms mounted 25 for swinging movement on said shaft, a driven shaft carried by each arm, a friction wheel mounted on each driven shaft, a pulley mounted on each driven shaft, a second set of pulleys mounted on the first mentioned shaft, belts connecting said first and second mentioned sets of pulleys, said arms being adapted for upward movement to move the friction wheels out of contact with the drums and means for holding said arms 35 in elevated position.
9. A photographic print washing machine including a bath containing element, a print containing element partly submerged therein, a driving means, and means for 40 communicating motion between the driving means and the print containing element including a wheel adapted to engage a portion of the print containing element and drive it by friction.
- 45 10. A photographic print washing machine including a bath containing element, a print containing element partly submerged therein, a constantly operated driving shaft, an arm mounted on the shaft and movable 50 thereabout, a driving element carried by the arm, means for communicating motion from the driving shaft to the driving element mounted on the arm, and means for raising and lowering the arms so as to bring 55 the driving element to or from an operative position in contact with a portion of the print containing element.
11. A photographic print washing machine including a bath containing element, 60 a rotary drum mounted therein, a rotating driving shaft, a movable arm, a friction wheel mounted thereon, means for rotating the friction wheel by means of the driving shaft, and a contact band on the rotary 65 drum, the drum being rotated by the friction wheel when contact is maintained between the friction wheel and the contact band by means of gravity.
12. A photographic print washing machine including a bath containing element 70 having an open top portion, a frame, a drum, means for supporting the drum upon the frame, a source of power, means including a friction wheel for driving the drum, the drum supporting and rotating means 75 being operable across the open top of the print bath containing element.
13. A photographic print washing machine including a bath containing element 80 having an open top and being adapted to contain a bath filling the element to a predetermined level, a print containing drum partly submerged therein, a source of power, a driving mechanism connected to the source of power, and means including the driving mechanism located above the level of the bath contained in the bath containing element 85 for rotating the drum.
14. In a photographic washing machine 90 including a bath containing element having side, bottom and end walls, a print carrying drum adapted to be partly submerged therein, a hinged member carrying the drum, said member being pivoted parallel to one wall of the bath containing element and having a portion of the hinged member adapted to contact with the top of another wall of the bath containing element thus holding the drum partly submerged in the bath containing element when 95 the hinged member is in one position.
15. In a photographic washing machine 100 including a bath containing element having side, bottom and end walls, a print carrying drum adapted to be partly submerged therein, a hinged member carrying the drum, said member being pivoted parallel to one wall of the bath containing element and having a portion of the hinged member adapted to contact with the top of another wall of the bath containing element 105 thus holding the drum partly submerged in the bath containing element, and a latch carried by a wall of the bath containing element for holding the drum and hinged member in a raised position when the hinged member is raised from its position in contact with the top of the bath containing element wall.
16. A photographic print washing machine 110 including a bath containing element, a drum suspended therein, a rotating shaft mounted along one side of the bath containing element, a friction wheel, a support therefor movable to and from an operative 115 position in which the wheel contacts with the drum, driving connections between the rotating shaft and the wheel, and means included in the support of the wheel for retaining by gravity the frictional driving 120
- 125
- 130

connection between the wheel and the drum when the roller support is in an operative position.

17. A photographic print washing machine including a bath containing element, a drum suspended therein, a rotating shaft, an arm hingedly connected thereto, a friction wheel carried by the arm, and driving connections between the rotating shaft and the friction wheel, the frictional driving connection between the wheel and the drum being maintained by gravity.

18. A photographic print washing machine including a bath containing element, a print containing drum adapted to be suspended therein, a power driven shaft, a pulley on the shaft, and a friction wheel, a supporting arm for the friction wheel mounted to turn upon the power shaft, a belt connecting the friction wheel and the shaft pulley, and means for moving the supporting arm to a position for rotating the drum through the friction wheel, said means also being adapted to move the roller

from the drum and out of driving relation therewith.

19. A photographic print washing machine including a bath containing element, a frame supporting the bath containing element, a drum binged to the frame and movable between an inoperative and an operative position in which it is suspended in the bath containing element, a driving element including a moving friction member hinged to the frame and being adapted to swing from an inoperative position to an operative position, when in its operative position said friction member resting on a portion of the drum and driving it by friction, and when in its inoperative position said friction member being out of contact with the drum regardless of the position of the drum.

In testimony whereof we affix our signatures.

IRVING POTTRUCK.
NORMAN SHALIT.
